UNITED STATES PATENT OFFICE.

ROBERT S. SHACKFORD, OF BROOKLINE, MASSACHUSETTS.

WRENCH.

Application filed March 26, 1920. Serial No. 368,856.

To all whom it may concern:

Be it known that I, ROBERT S. SHACKFORD, a citizen of the United States, residing at Brookline, in the county of Norfolk and State of Massachusetts, have invented certain Improvements in Wrenches, of which the following description, in connection with the accompanying drawings, is a specification, like reference characters on the drawings indicating like parts in the several figures.

This invention relates to wrenches and more especially to that type of wrench which is automatically adjustable to the nut or bolt head on which it is working. The invention aims to devise a wrench of this character which shall be simple in construction, convenient to operate, and which can be economically manufactured.

The manner in which it is proposed to accomplish these objects will be readily understood from the following description when read in connection with the accompanying drawings, in which—

Figure 1 is an isometric view of a wrench embodying the present invention; and

Figure 2 is a plan view of the head portion of the wrench shown in Fig. 1.

The construction shown comprises a head consisting of two plates 2 and 3, respectively, properly spaced apart. Integral with this head is a jaw 4 comprising suitably shaped extensions of the plates 2 and 3 with a spacing block 5 between them, these three parts being secured together by rivets 6. The movable jaw 7 of the wrench comprises a central plate 8 of the same thickness as the block 5 and two outside pieces 9 of the same thickness as the plates 2 and 3, the parts 8 and 9 being secured together by rivets 10. An extension from the central member 8 of the movable jaw is mounted within the head and forms a shank for the jaw. This shank is slotted, as indicated at 11 and 12, to receive pins 13 and 14 which are secured in the plates 2 and 3 and cooperate with the slots to guide the movable jaw so that it can slide in a straight line toward and from the fixed jaw 4. A spring 15 positioned in the slot 11 bears at one end against the end of this slot and at the other end against the pin 13 and thus tends to hold the movable jaw 7 toward the fixed jaw 4. In other words, this spring tends to close the jaws.

A handle 16 is secured to the head of the wrench by a pivot 17 and is provided with a cam shaped projection 18 that bears against a cooperating projection 19 on the shank of the movable jaw. Another projection 20 from this shank engages the side of the cam shaped projection 18 opposite that engaged by the part 19.

It will now be clear that when the handle 16 is swung in a clockwise direction, as the parts appear in Fig. 2, the cam part 18 acting on the member 19 will force the movable jaw 7 toward the fixed jaw 5, or, in other words, will close the wrench on the nut or bolt head N on which the wrench is working. When the handle 16 is swung in the opposite direction the engagement of the cam 18 with the projection 20 will open the jaws and thus free the jaws from the nut and enable the wrench to be turned to obtain a new "bite" on the nut. Obviously the jaws will be closed up again on to the nut during the first part of the next clockwise movement of the handle 16. If the nut or bolt on which the wrench is working is to be backed out or has a left-hand thread the wrench would simply be turned over before work on the nut or bolt is begun. When the wrench is idle the spring 15 tends to hold the jaws closed and also tends to hold the handle 16 at the left-hand limit of its movement, as it appears in Fig. 2.

It will be seen from the foregoing description that the invention provides an exceedingly simple form of wrench which is convenient to use and which automatically adjusts the jaws to the nut or bolt on which the wrench is working. Furthermore, the invention provides a construction that can be very economically manufactured. All the parts at the head of the wrench can be stamped or punched of sheet metal, and the handle also can be produced in this way, or if a heavier handle is required it can be cast or made by drop forging. The rivets 13, 14 and 17, in addition to the function above described, also perform the function of holding the plates 2 and 3 in their properly spaced relationship, the outer ends of the rivets for this purpose being headed or expanded.

What is claimed as new is:

1. A wrench of the character described, comprising a hollow head, a jaw rigid with said head, another jaw having a shank portion slidable in said head toward and from

the first jaw, a pin fixed in said head transversely of the sliding movement of said jaw, said shank having a slot therein through which said pin passes, a spring in said slot tending to urge said jaws toward each other, a handle pivoted in said head, and a cam projection extending therefrom toward said 5 slidable jaw, said slidable jaw having a projection engaged by said cam whereby a swinging movement of said handle in one direction operates to force said slidable jaw toward its companion jaw.

2. A wrench of the character described, comprising a hollow head, a jaw rigid with

said head, another jaw having a shank portion slidable in said head toward and from the first jaw, said shank having two parallel slots formed therein, pins fixed transversely in said head and positioned in said slots whereby the second jaw is guided relatively to the first jaw, a handle pivoted in said head and having an extension projecting into a recess formed in said slidable jaw, and a spring acting between said head and slidable jaw to close said jaws.
